CABINET FOR A WALL SYSTEM

Joseph Reiter, 11255 Suzor Cote,
Montreal, Quebec, Canada

Filed Feb. 16, 1972, Ser. No. 227,016

Term of patent 14 years

Int. Cl. D6—04

U.S. Cl. D6—130

FIG. 1

FIG. 2

FIG. 6

FIG. 1 is a front elevation of a cabinet showing in dotted lines the railings on which it is normally mounted; FIG. 2 is a perspective view of the cabinet; FIG. 3 is a top plan view thereof; FIG. 4 is an enlarged front elevation thereof; FIG. 5 is an end elevation view of the cabinet; and FIG. 6 is a fragmentary enlarged perspective view of one corner of the cabinet.

The broken lines are shown for illustrative purposes only.

In the cabinet shown, the characteristic feature residing in a plurality of mutually parallel, juxtaposed, curved corner elements butting at opposite ends with aligned side elements, juxtaposed to form side panels, in which the grain of the corner elements and side elements extend in parallel banding patterns around the periphery of the cabinet.

I claim:

The ornamental design for a cabinet for a well system, as shown and described.
